A. O. RUTZ.

COMBINED SIMMERER AND FLASH IGNITER FOR GAS STOVES.

APPLICATION FILED JUNE 14, 1916.

1,251,112.

Patented Dec. 25, 1917.

UNITED STATES PATENT OFFICE.

ARNOLD O. RUTZ, OF MILWAUKEE, WISCONSIN.

COMBINED SIMMERER AND FLASH-IGNITER FOR GAS-STOVES.

1,251,112.

Specification of Letters Patent. Patented Dec. 25, 1917.

Application filed June 14, 1916. Serial No. 103,633.

To all whom it may concern:

Be it known that I, ARNOLD O. RUTZ, a citizen of the United States, and resident of Milwaukee, in the county of Milwaukee and 5 State of Wisconsin, have invented certain new and useful Improvements in Combined Simmerers and Flash-Igniters for Gas-Stoves; and I do hereby declare that the following is a full, clear, and exact description thereof.

The present invention relates to new and useful improvements in gas stoves and is directed more particularly to the simmering burner and flash igniter structures thereof.

15 It is primarily the object of the present invention to combine the flash igniter structure and the simmering burner structure of a gas stove in an exceedingly simple and compact manner, and further in a manner 20 wherein the flash igniter structure is carried entirely by and housed within the simmering burner structure.

The present invention contemplates the provision of a combined valve structure for 25 the simmering burner and the flash igniter burner, and in this connection it is further an object of the present invention to utilize this valve arrangement as a master valve control for the flash burner valve structure, 30 whereby this master valve may be actuated to entirely shut off flow of gas through the flash igniter structure, providing more particularly for shutting off the usual pilot light of the flash igniter, it being appreciated that, although a valve is usually associated with the pilot light by-pass, this 35 valve is of such nature, and procures such necessarily fine adjustment that it is not adapted for manipulation to temporarily 40 shut off the flow.

With the above and other objects and advantages in view the invention resides more particularly in the novel combination, arrangement and formation of parts more particularly hereinafter described and pointed 45 out in the appended claims.

In the drawings:

Figure 1 is an elevational view of a combined flash igniter and simmerer constructed 50 in accordance with the present invention, with the valve and portions of the burner structure in section.

Fig. 2 is a transverse sectional view 55 through the valve structure on the line 2-2 of Fig. 1 showing the simmering burner valve ports.

Fig. 3 is a similar sectional view through that portion of the valve structure including the igniter burner valve ports as indicated by the line 3-3 of Fig. 1.

Fig. 4 is a top plan view of the burner head structure.

Referring now more particularly to the accompanying drawings, the combined valve structure includes a main casing 5 having 65 its bore taperingly reduced toward its lower end in the usual manner of gas stove valves for the reception of a similarly tapered valve head 6 to the lower end of which is secured the handle 7. Extended from one 70 side of the casing is a nipple 8 whereby the casing is secured to the usual main supply pipe 9 at the front of the stove and extending from the opposite side of the casing is a boss 10 for the securement of the burner 75 pipes.

This valve head controls the flow of gas to the simmering burner, and it also comprises a master valve for the igniter valve structure, which valve structure is preferably of the type embodied in my former application for patent filed April 14, 1916, 80 Serial No. 91125, wherein is provided a plunger valve and by-pass valve which are embodied in a single unit detachable from 85 the casing and in the present instance the main valve 6 serves as a casing, being provided with a well 11 extending downwardly through its major portion which is threaded to receive the plunger valve cage 12. The 90 lower end of this cage forms a valve seat engageable by the head 13 of the plunger valve, whose stem 14 extends upwardly through the cage and terminates in the button 15, the head 13 being normally urged 95 to closing position by a spring 16 disposed within the upper portion of the cage and bearing against the button and against a suitable gasket means within the cage.

The intermediate peripheral portion of the 100 cage is cut away to form, in conjunction with the adjacent well wall portion, an annular chamber 17 which communicates with the interior of the cage. The by-pass arrangement embodied in this igniter valve structure 105 comprises a longitudinal passage 18 through the valve head 13 and stem 14 which communicates with the interior of the cage by a lateral port 19 in the stem. Disposed in the longitudinal passage is a valve pin 20 which extends below the port 19 and which has one side portion adjacent and below the 110

said port cut away to provide a passage communicating with the port and adjustable upon rotation of the stem to regulate the flow through the by-pass.

5 The boss 10 of the main casing is offset upwardly from the nipple 8, and extending through the nipple 8 are inlet and outlet simmering supply ports 21 and 22 respectively, which are adapted to align with openings 21^a and 22^a respectively formed in the adjacent wall portion of the main valve head 6, the opening 21^a being extended transversely in the wall whereby to permit access of gas into the well of the main valve head, when the outlet port 22 is shut off. Above the outlet port 22 a flash supply port 23 is formed in the casing and boss 10, which port at its inner end is normally in alignment with a transversely elongated opening 24 formed in the adjacent wall portion of the main valve, this opening 24 being in communication with the annular chamber 17 of the igniter valve.

Thus in the normal manipulation of the valve head 6 to open and close the simmering burner outlet port 22, the main inlet port 21 and the flash burner outlet port 23 are at all times open to permit independent operation of the flash burner valve. The valve head 6 is normally held within such limits of rotation as to retain the above mentioned relation by a pin 25 projecting laterally from the upper portion of the valve head to engage in a suitable cut away portion of the casing for abutment with the sides of said cut away portion, this cut away portion of the casing being coextensive with the transversely extended opening 21^a of the main valve head 6.

40 It is seen that movement of the valve head past its normal limits of movement will shut off the main supply port 21, to consequently shut off flow also through the flash burner valve structure. Thus the valve 6 45 may serve as a master valve for the flash burner valve structure, which comprises an auxiliary valve means in the main valve, and which includes the main flash valve and the by-pass valve. To procure this complete 50 shut off operation of the valve 6, the pin 25 may be removed or suitably adjusted with respect to its relation to the valve head and the cut away portion of the casing.

The simmering burner of the present invention comprises a flat top wall 26 provided adjacent its periphery with a series of jet apertures 27 and depending side walls which merge into a lateral neck portion 28 in which is threadedly engaged one end of the simmering burner pipe 29, the other end of which pipe is slidably engaged on the boss 10. Threaded in the upper portion of the boss to communicate with the flash burner is a flash supply pipe 30 and this pipe extends 65 through the pipe 29 and has its end curved

upwardly within the simmering burner and extended through the top wall thereof adjacent one side for threaded engagement with the flash burner head 31, a suitable stop nut 32 being provided on the pipe 70 within the simmering burner to bear against the top plate thereof whereby a firm securement of the flash burner to the simmering burner may be had. In assembling this structure the flash supply pipe 30 is extended 75 into the simmering burner and secured by attachment of the flash burner head 31, the simmering supply pipe 29 is then threaded into the simmering burner and the flash burner supply pipe is threaded into the boss 80 10, while the adjacent end of the simmering supply pipe slides over the said boss.

To provide for proper admixture of air with the gas in the simmering supply pipe, said pipe is provided in its lower portion 85 adjacent the boss 10 with an air port 33 and the adjacent end of the simmering outlet port of the valve is restricted to form a nozzle. Thus gas is supplied to the simmering burner at a pressure but slightly 90 above atmospheric pressure, while the gas supply to the flash burner is at the pressure of the gas main, whereby flames may be projected by the flash burner a sufficient distance to ignite the various main burners of 95 the stove.

To provide a shield for the pilot light of the flash burner, an arcuate upstanding shield plate 34 is secured at the front portion of the simmering burner by attachment 100 to upstanding peripheral lugs 35 thereon and this plate is provided with ports 36 in alignment with the forwardly disposed main burners and their respective flash burner apertures. The upper portion of this shield 105 plate carries an inwardly extending top wall 37 which, at its intermediate portion projects over the flash burner to protect it from drippings. Inasmuch as drafts do not usually occur from the back portion of a 110 stove due to its normal positioning against the wall, the present shield structure serves to efficiently guard against such drafts as would tend to blow out the pilot light.

The present arrangement occupies but 115 little more space than either the simmering burner structure or the flash igniter structure alone and consequently conduces materially toward a desired compactness of stove structure, in addition to the provision of a 120 central positioning of both the simmering and flash igniter burners and a master valve control for the flash burner valve.

I claim:

1. In a structure of the class described, a 125 main supply pipe, a simmering burner, a flash igniter burner, and a unitary valve connected with the burners and supply pipe and including means for providing a constant limited flow of gas to the igniter 130

- burner, means for controlling the flow of gas to the simmering burner, and means for intermittently increasing the flow of gas to the igniter burner to produce a flash.
5. 2. In a structure of the class described, a main supply pipe, a simmering burner, a flash igniter burner and a unitary valve connected with the burners and supply pipe, and including means for providing a constant limited flow of gas to the flash igniter burner, means for controlling the flow of gas to the simmering burner, said means also being adapted to cut off the limited flow to the flash igniter burner and means for intermittently increasing the flow of gas to the igniter burner when the same is provided with a limited flow whereby to produce a flash.
10. 3. In a structure of the class described, a pair of burners, and a valve for controlling the flow of fluid thereto comprising a casing having a pair of outlets communicating with the burners, a hollow body portion rotatable therein and having an inlet and an opening communicating with one of the outlets in the casing, and a stem slidable through the body portion, said stem having a longitudinal passage and a lateral passage communicating respectively with the interior of the hollow body and the other of said outlets in the casing whereby to provide a constant flow of fluid to one of said burners.
15. 4. In a structure of the class described, a pair of burners, and a valve for controlling the flow of fluid thereto comprising a casing having a pair of outlets communicating with the burners, a hollow body portion rotatable therein and having an inlet and an opening communicating with one of the outlets in the casing, a stem slidable through the body portion, said stem having a longitudinal passage and a lateral passage communicating respectively with the interior of the hollow body and the other of said outlets in the casing whereby to provide a constant flow of fluid to one of said burners, and a pin slidably disposed in the longitudinal passage and having one end portion adjacent the lateral passage cut away to adjustably control the flow of fluid through said passages.
20. 5. A combined simmerer and flash igniter comprising a valve casing provided with a
- boss in which is disposed a pair of independently controllable outlet ports, a simmering burner, a flash burner carried by the 55 simmering burner, a pipe extending from the simmering burner and slidably engageable on the boss, a second pipe extending from the flash burner and disposed within the first pipe and threadedly engaged in the 60 boss for communication with one of the ports, and the first named pipe being provided with an air port adjacent the boss.
6. A combined simmerer and flash igniter comprising a simmering burner, a flash 65 burner carried by the simmering burner adjacent the forward side thereof, valve means for supplying gas to the burners and an upstanding arcuate shield at the side portion of the simmering burner adjacent the flash 70 burner provided with ports alining with certain of the flash burner apertures.
7. A combined simmerer and flash igniter comprising a simmering burner including an apertured top portion and depending wall 75 portion merged into a lateral neck, a simmering supply pipe secured to said neck, a flash supply pipe disposed in the first pipe and having its adjacent end extending laterally through the simmering burner and a 80 flash burner secured on the said end of the flash supply pipe.
8. In a structure of the class described, a valve including a hollow body portion, a stem slidably passed through said body portion; a head on one end of the stem adapted to abut the body portion, said stem and head being provided with a longitudinal passage entirely therethrough and the stem being provided with a lateral passage communicat- 90 ing with the interior of the body portion, and a pin rotatably passed into the longitudinal passage and having one end portion adjacent the lateral passage cut away to adjustably permit flow of fluid through said 95 longitudinal and lateral passages.

In testimony that I claim the foregoing I have hereunto set my hand at Milwaukee, in the county of Milwaukee and State of Wisconsin, in the presence of two witnesses. 100

ARNOLD O. RUTZ.
